A. HABERL

CRIB

Filed Nov. 17, 1925

UNITED STATES PATENT OFFICE.

ALOIS HABERL, OF ST. CLAIR SHORES, MICHIGAN.

CRIB.

Application filed November 17, 1925. Serial No. 69,652.

This invention relates to certain improvements in cribs and an object of the invention is to provide a device of this kind which may be readily assembled or taken down as desired.

Another object of the invention is to provide a device of this kind provided with means whereby the occupant is effectively protected against insects and the like.

10 The invention consists in the details of construction and in the combination and arrangement of the several parts of my improved crib whereby certain important advantages are attained and the device rendered simpler, less expensive and otherwise more convenient and advantageous for use, as will be hereinafter more fully set forth.

The novel features of my invention will hereinafter be definitely claimed.

20 In order that my invention may be the better understood, I will now proceed to describe the same with reference to the accompanying drawings, wherein:—

Figure 1 is a longitudinal vertical sectional view taken through a crib constructed in accordance with an embodiment of my invention;

25 Figure 2 is a fragmentary vertical sectional view taken through the housing for the top screen as herein disclosed;

30 Figure 3 is a fragmentary view in top plan of the structure as illustrated in Figure 2;

Figure 4 is a view in perspective of the 35 top screen unapplied and substantially entirely rolled;

40 Figure 5 is a view of somewhat a diagrammatic character illustrating the means herein employed for holding the sections of the crib in assembled relation.

As herein disclosed, my improved crib comprises the end sections A and B denotes a side section, it being understood that two of such sections B are employed. The end sections A include the corner posts 1 each of which having positioned thereon at desired points a plate 2 having a keyhole slot 3 to provide means whereby a headed member 4 carried by a side section B may be readily interlocked with the plate 2 and thereby hold the end and side sections in assembled relation yet at the same time permitting a ready separation when it is desired to knock down the crib.

55 Each of the end and side sections A and B comprises the screened panels 5 and the

crib bottom, as herein disclosed, consists of a conventional type of spring S supported by the inwardly disposed brackets 6 carried by the posts 1. Extending along the top 60 rail 7 of one of the end sections A is a housing or casing H the same projecting beyond the opposite sides of said section as particularly illustrated in Figure 3 of the drawings. The housing or casing H 65 is substantially semi-circular in cross section and has one longitudinal marginal portion 8 tangentially disposed and terminating in an outstanding flange 9 which, when the housing or casing H is in applied position, is adapted to be attached to the top rail 7. The ends of the housing or casing H are normally open but each of said end portions is closed by a head 10 having its peripheral portion provided therearound with the inwardly disposed fingers 11 alternately overlapping the outer and inner faces of an end portion of the housing or casing H as is particularly illustrated in Figures 2 and 3 of the accompanying drawings. Each 70 of the heads 10 is provided with an extended portion 12 terminating in an inwardly disposed angular flange 14 adapted to contact with the adjacent end of the rail 7 and suitably secured thereto whereby the housing 75 or casing H is further maintained in applied position.

The upper marginal portion of the housing or casing H, when the same is in applied position, is spaced from the rail 7 80 providing a slot 15 through which a cloth screen 16 may readily pass. The screen 16 is adapted to be wound upon a conventional screen roller 17 mounted within the housing or casing H. When extended, the screen 85 16 extends across the top of the crib and has its outer end portion provided with the eye members 18 each of which being adapted to have engagement with a hook 19 carried by the top rail 7' of the opposite end section A. When the screen 16 is freed from the rail 7' such screen will readily wind upon the roller 17 and be substantially confined within the housing or casing H when such screen 16 is not in use.

105 From the foregoing description it is thought to be obvious that a crib constructed in accordance with my invention is particularly well adapted for use by reason of the convenience and facility with which 110 it may be assembled and operated, and it will also be obvious that my invention is

susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

- 10 1. A crib comprising end sections, side sections and a bottom, a housing disposed along the upper portion of one of the end sections, a roller within the housing, a screen adapted to wind upon said roller and be confined substantially within the housing when not in use, said screen when extended being disposed across and closing the top of the crib, the outer end of said screen, and the second end section of the crib being provided with coacting means for holding said screen in its extended position, said housing having its opposite ends initially open, a head for each end of the housing being provided with inwardly disposed fingers, said
- 15 2. A crib comprising end sections, side sections and a bottom, a housing disposed along the upper portion of one of the end sections, a roller within the housing, a screen adapted to wind upon said roller and be confined substantially within the housing when not in use, said screen when extended being disposed across and closing the top of the crib, the outer end of said screen, and the second end section of the crib being provided with coacting means for holding said screen in its extended position, said housing having its opposite ends initially open, a head for each end of the housing being provided with inwardly disposed fingers, said
- 20 3. A crib comprising end sections, side sections and a bottom, a housing disposed along the upper portion of one of the end sections, a roller within the housing, a screen adapted to wind upon said roller and be confined substantially within the housing when not in use, said screen when extended being disposed across and closing the top of the crib, the outer end of said screen, and the second end section of the crib being provided with coacting means for holding said screen in its extended position, said housing having its opposite ends initially open, a head for each end of the housing being provided with inwardly disposed fingers, said

fingers alternately engaging the outer and inner faces of the housing.

2. A crib comprising end sections, side sections and a bottom, a housing disposed along the upper portion of one of the end sections, a roller within the housing, a screen adapted to wind upon said roller and be confined substantially within the housing when not in use, said screen when extended being disposed across and closing the top of the crib, the outer end of said screen, and the second end section of the crib being provided with coacting means for holding said screen in its extended position, said housing having its opposite ends initially open, a head for each end of the housing being provided with inwardly disposed fingers, said

3. A crib comprising end sections, side sections and a bottom, a housing disposed along the upper portion of one of the end sections, a roller within the housing, a screen adapted to wind upon said roller and be confined substantially within the housing when not in use, said screen when extended being disposed across and closing the top of the crib, the outer end of said screen, and the second end section of the crib being provided with coacting means for holding said screen in its extended position, said housing having its opposite ends initially open, a head for each end of the housing being provided with inwardly disposed fingers, said

4. In testimony whereof I hereunto affix my signature.

ALOIS HABERL.
